UNITED STATES PATENT OFFICE.

JOHN WIGHTMAN, OF NOTTINGHAM, ENGLAND.

DESIGN FOR RUFFLING AND RUCHING.

SPECIFICATION forming part of Design No. 21,562, dated May 24, 1892.

Application filed April 20, 1892. Serial No. 429,956. Term of patent 3½ years.

To all whom it may concern:

Be it known that I, JOHN WIGHTMAN, a subject of the Queen of Great Britain, residing at Nottingham, England, have invented and produced a new and original Design for Rufflings and Ruchings, of which the following is a specification, reference being had to the accompanying drawing, forming a part thereof, which represents a perspective view of a piece of ruching embodying the features of my design.

The design consists of a series of fringe-like essentially-circular figures A, having somewhat of a feathery appearance, the figures be-

ing distinct from or independent one of the other, and said figures are arranged in rows along the edge of a band-like figure B. The two rows of fringe-like or feathery figures appear back to back and as curling over opposite sides of the band-like figure, yet constituting no portion of the latter.

I claim—

The design for ruffling and ruching, as herein shown and described.

JNO. WIGHTMAN.
